UNITED STATES PATENT OFFICE.

CHARLES C. GRUHLER, OF FORT THOMAS, KENTUCKY.

CARD-MOUNTING MEANS.

Application filed August 10, 1925. Serial No. 49,399.

The invention relates to improvements in means for mounting index and analogous cards upon supports, such as slide trays of filing cabinets, the principal object being to 5 provide simple and inexpensive yet efficient means for pivotally and detachably mounting the cards in such a manner that they may readily be relatively adjusted for the insertion or removal of cards and may be 10 swung about their pivots to expose either of their sides for use.

With the foregoing in view, the invention resides in the novel subject matter herein-after described and claimed, the description 15 being supplemented by the accompanying drawings.

Figure 1 is an elevation disclosing the invention in use for mounting a plurality of cards upon a tray.

20 Figure 2 is a side view.

Figure 3 is an end elevation partly in section as indicated by line 3-3 of Fig. 1.

Figure 4 is a detail elevation similar to a portion of Fig. 3 but illustrating the manner in which the card-carrying clips may be readily engaged with or disengaged from tracks which are mounted on the support or tray.

Figure 5 is a detail sectional view illustrating the manner in which the card may be readily swung upon its pivotal mounting means.

Figure 6 is an elevation partly broken away, showing one of the cards and the clip-carried pivot pins thereof.

In the drawings above briefly described, the numeral 1 designates a support which may be considered as a sliding tray or drawer of a filing cabinet. Secured to this tray, 40 are two parallel tracks 2, said tracks having overhanging side walls 3, disposed in laterally spaced relation. Below these tracks is a shelf 1^a upon which the lowermost of the cards, hereinafter described, may rest. 45 Spring clips 4 are readily engageable with and disengageable from the tracks 2, each clip being preferably formed from a single spring-metal strip whose central portion is bent substantially upon itself in the form 50 of a U as indicated at 5, the arm portions 6 of the U being bent outwardly at 7 substantially upon themselves with extensions to provide a pair of outer, relatively movable arms 8, the free ends of these arms converging at 8' and then terminating in diverging 55 relation as indicated at 8'' to engage the outer sides of the walls 3. By grasping the outer ends of the clip 4 between the thumb and the forefinger, it may be laterally compressed so that its end portions 8'-8'' will 60 be separated and may be readily disengaged from the track or engaged with it as occasion may demand.

The portions 6 and 7 of each clip 4 are formed with alined openings 9, the openings of the numerous clips receiving pivot pins 10 in a removable manner. These pins are carried by additional spring-metal clips 11 which detachably engage corners of the cards 12. As long as the clips 4 for any card, 70 are engaged with the tracks 2, the pins 10 cannot move out of the openings 9 unless the card is first disengaged from one or the other of its clips 11. When this is done, however, or when pins 10 for any card are 75 disengaged from the clips 4, removal of any card and its pivot pins is permitted, yet the clips 4 for carrying such card may be left in the tracks 2, readily indicating the point from which the card has been removed, thus 80 greatly facilitating its reinsertion or the insertion of another card to take its place. Also, if desired, if a card is in wrong alphabetical arrangement, the card and clips 4 are removed from the track 2. Then, the 85 balance of the cards are pushed up or down the clips 4 sliding on the track 2 so that the space for replacement of the card is in proper place and the clips 4 are put on track 2 and the card put in. This also permits removal of cards no longer required, and the 90 substitution of other cards in another place.

Considering the members 11 in another light, they may be termed "spring" steel slip-on clips with pin extensions 10. They can 95 be removed from discarded cards and used again, or readily replaced if broken or damaged. Whenever desired, the cards may be swung about their pivots so that either their front or rear sides are accessible, and this 100 pivotal movement permits cards overlying any other card or cards to be swung back to give access to the latter. By having the clips 11 slidably engageable with or discon-nectable from the cards 12, a typewriter may 105 well be used, in making entries on such cards, should this be desired. Moreover, the cards may be kept compactly stacked before their use is necessary and a number of the clips 11 with pivot pins 10 may be compactly re-tained in an appropriate container. Then, 110 whenever a new card is necessary, it may

be taken from the stack and a pair of clips applied to it. The detachable connection between the clips 4 and 11 is not only of advantage in adding and removing the cards, but permits the clips 4 to be kept segregated from other parts of the device so that two or more may be readily located whenever their use is required.

The invention is exceptionally simple and inexpensive, yet is very efficient and desirable, and as excellent results may be obtained from the general construction shown, such construction is by preference followed. However, within the scope of the invention as claimed, modifications may be made.

It may be added, that if desired, the tracks 2 may downwardly taper as shown in Fig. 2, permitting the cards to lie flat upon each other for use while still attached to the holding means.

I claim:

1. In a means for mounting a plurality of index or analogous cards on a support; parallel tracks carried by the support, a pair 25 of spring clips for each card readily engageable with and disengageable from said tracks, an additional pair of spring clips detachably engaged with corners of each card, and detachable pivotal connections between the track-engaging and card-engaging clips.
2. In a means for mounting a plurality of index or analogous cards on a support; parallel tracks on the support having overhang-

ing side walls, a pair of spring clips for each 35 card provided with relatively movable arms engaging said overhanging side walls, said clips being removable from the tracks by effecting relative lateral movement of their arms, and pivots connecting each card with 40 its respective clips.

3. In a means for mounting a plurality of index or analogous cards on a support; parallel tracks on the support having overhanging side walls, a pair of spring clips for each 45 card provided with relatively movable arms engaging said overhanging side walls, said clips being removable from the tracks by effecting spreading of their arms, and pivots connecting each card with its respective 50 clips.

4. A structure as specified in claim 3; each clip comprising a single spring-metal strip having its central portion bent into U-shape, and its end portions bent outwardly 55 and back against the sides of the U and extended beyond the arm-connecting portion of the U to provide said relatively movable arms, the free ends of the latter being bent to properly shape them for engagement with 60 the overhanging side walls of the coating track, the double side portions of the U having aligned openings removably receiving said card pivots.

In testimony whereof I have hereunto affixed my signature.

CHARLES C. GRUHLER.
